CLIPPER STERILIZER

Stanley Waraner, Chicago, Ill.

Application July 29, 1947, Serial No. 764,280

6 Claims. (Cl. 21—88)

1

This invention relates to improvements in accessories to the barbers' trade and more particularly to sterilizers for hair clippers and the like and an object is to provide a sterilizer adapted for use with hand clippers as well as with electric clippers. The instant invention is a further development of the invention disclosed in my co-pending application entitled Clipper sterilizers, Serial Number 716,323, filed December 14, 1946.

In previous inventions of this nature the procedure has been, to the best of my knowledge, to take the clipper to the sterilizer whereas in the instant case the sterilizer is brought to the clipper. The advantages of this are manifold. In the art of hair cutting it is necessary for the operator to use his clipper alternately with his shears. During the periods of use of the shears with the clipper at rest the sterilizer may be applied without appreciable loss of time so that the process of sterilization is practically continuous thus assuring the greatest degree of sanitation. The sterilizer is adapted for instant application to and removal from the clipper and where an operator is provided with but one clipper he may keep it under practically constant sterilization. The present clipper is of a "snap on" type making its application and removal all but automatic. When using an electric clipper the sterilizer is applied without detaching the electric cord and without interference therewith.

An object also of the present invention is to provide a clipper sterilizer of simple compact construction that is highly efficient in use and inexpensive to manufacture and one that when applied practically seals itself to the clipper preventing the escape of any odors of the sterilizing agent employed.

With the foregoing and other objects in view the invention consists in the combination and arrangement of parts to be hereinafter fully set forth, defined in the claims and illustrated in the accompanying drawing forming part of this disclosure.

In the drawing:

Fig. 1 is a top plan view partly in section and partly broken away of a clipper sterilizer embodying the features of the instant invention.

Fig. 2 is a view in side elevation of the sterilizer shown in Fig. 1 with a portion of a clipper serviced thereby shown in dotted lines.

Fig. 3 is a longitudinal vertical sectional view through Fig. 1 on the line 3—3 but illustrating

two positions of the adjustable member and of the clipper.

Fig. 4 is a view similar to Fig. 3 but with the cylinder-like container omitted and the adjustable drawer ready to be applied to the carrier frame previous to complete assembly.

Fig. 5 is a view in perspective of the adjustable drawer employed, and,

Fig. 6 is a front end view of the carrier frame taken on the line 6—6 of Fig. 4.

Like reference characters denote corresponding parts throughout the several views.

The instant clipper sterilizer includes a frame or carrier portion 1 having a preferably oblong flat base 2 and inclined top wall 3 separated from said base by the side walls 4, the top and base being co-extensive, the top wall being substantially notched inwardly from its lower edge in approximately U-shape, the base of the opening extending transversely of the top wall at about its longitudinal center, the sides of the opening being spaced inwardly slightly from the top wall lateral edges but diverging slightly from the U base, the mouth of the opening being at the narrow truncate end of the carrier frame. The ends of the side walls at the wider end of the carrier are recessed semi-circularly to receive the transversely disposed cylindrical container 5 of a length commensurate with the width of the carrier.

The outside diameter of said container is equal to the distance between the outer faces of the top and base walls at their points of engagement with said container which is peripherally recessed to receive said wall ends and cemented or sealed thereto, that portion of the wall of said cylinder between the top and base being formed with a plurality of slots 6, the mouth or open end of the cylinder container being thickened slightly and threaded interiorly to receive the screw cap 7, said container carrying a sterilizing agent such as formaldehyde or the like.

Extending along the inner face of each side wall from end to end thereof and from the top wall is a cleat or rib 8 formed at a point spaced inwardly a short distance from the truncate or narrow end of the carrier frame with a square shoulder 9, the lower or free edge of said rib on both sides of said shoulder being parallel to the base 2. Adjustably disposed in the carrier frame and received through the wider end thereof before the cylindrical container is put in place is the drawer 10, its open end disposed toward the container, slidable upon base 2, the side walls 11 being thickened at their free ends

12 and formed with inwardly disposed V-shaped notches 13, one side of each notch being longer than the other. Formed or provided upon the relatively remote corners of the thickened portions 12 of the side walls of the drawer are the lugs 14 rising slightly above said walls. The drawer is of slightly greater width than the space between the ribs 8 and of such height that they ride thereagainst to one side of shoulders 9 while the lugs are of such height that they ride against said ribs at the opposite side of said shoulders, as the drawer is adjusted back and forth, the lugs engaging the shoulders when the drawer is moved outwardly through the truncate end of the carrier frame to full line position, Fig. 3.

The lateral portions of the top wall 3 opposite the cut out overlie the side walls of the drawer but the space between the top wall portions and the side walls of the drawer is sufficient to receive the lateral edges of the lower tooth plate of the clipper 15 the blade end of which is received in the drawer in its extended position, the ends of the blades or teeth riding into the V notches 13, the clipper then riding with the drawer into the carrier frame until the clipper moves into abutment with the base and sides of the U-shaped cut out or notched portion of the top wall, the clipper resting with its blade end in the drawer and upon the end wall 16 thereof and forming a snug fit or "seal" therewith, the clipper blades being now disposed in close proximity to the slotted portions of the container 5 to be sterilized by the agent carried thereby. The sterilizer is made in sizes to accommodate the several sizes of standard clippers, clearance of about $\frac{1}{8}$ inch being allowed in the drawer width over the clipper width so that an easy practically "automatic" instant application of the clipper to the sterilizer or removal therefrom may be made in an effortless manner with but very little practice.

What is claimed is:

1. In a clipper sterilizer, a carrier frame having a flat base and an inclined top wall having a notch extending inwardly from one end thereof to snugly receive the clipper, side walls connecting said base and top wall, a perforate container at one end of said carrier frame snugly engaging said base, top and side walls; a drawer adjustably received in said carrier frame and movable back and forth into extended and telescoped position with respect thereto cooperating in its extended position with the notched portion of said top wall to receive one end of a clipper and in its telescoped position to snugly embrace the clipper end, and guide means for said drawer connecting same and said carrier frame.

2. In a clipper sterilizer, an open ended carrier frame having a flat base and an inclined top wall having a notch extending inwardly from one end thereof to snugly receive the clipper, side walls connecting said base and top wall, a perforate container closing one end of said carrier frame with its perforate portion opening thereto, a drawer adjustably received in said carrier frame

movable back and forth through the other open end thereof and cooperating in one position with the notched portion of said top wall to receive one end of a clipper and in a second position to snugly embrace the clipper end, and guide means for said drawer connecting same and said carrier frame.

3. In a clipper sterilizer, an open ended carrier frame having a flat base and an inclined top wall having a notch extending inwardly from one end thereof to snugly receive the clipper, side walls connecting said base and top wall, a perforate container closing one end of said carrier frame with its perforate portion opening thereto, a drawer adjustably received in said carrier frame movable back and forth through the other open end thereof and cooperating in one position with the notched portion of said top wall to receive one end of a clipper and in a second position to snugly embrace the clipper end, guide ribs extending longitudinally of said side walls engaging said top wall and said drawer, and lugs carried by said drawer engaging said ribs.

4. In a clipper sterilizer, a truncate carrier frame having a flat base and an inclined top wall having a notch extending inwardly from one end thereof to snugly receive the clipper, side walls connecting said base and top wall, a perforate container at one end of said carrier frame opening thereto and snugly engaging said base, top and side walls; a drawer adjustably received in said carrier frame and movable back and forth through the truncate end thereof and cooperating in one position with the notched portion of said top wall to receive one end of a clipper and in a second position to snugly embrace the clipper end, guide ribs extending longitudinally of said side walls engaging said top wall and said drawer, lugs carried by said drawer engaging said ribs, and notches in said

40 drawer receiving the ends of the clipper.

5. In a clipper sterilizer, a frame having one open end and a top wall having a notch extending inwardly from one edge thereof to snugly receive the clipper, a container at one end of said frame opening thereto, and a drawer telescopically received in the open end of said frame cooperating with said top wall notch in one position to receive a clipper and in a second position to snugly engage the clipper.

6. In a clipper sterilizer, a frame having one open end and a top wall having a notch extending inwardly from one edge thereof to snugly receive the clipper, a container at one end of said frame opening thereto, a drawer telescopically received in the open end of said frame cooperating with said top wall notch in one position to receive a clipper and in a second position to snugly engage the clipper, and means connecting said frame and drawer for guiding the latter in its movements and for limiting the extent of its movement relative to said frame in one direction.
